UNITED STATES PATENT OFFICE.

MILTON F. CHESHIRE, OF CHICAGO, ILLINOIS, ASSIGNOR TO CHESHIRE COMPANY,
INCORPORATED, OF CHICAGO, ILLINOIS.

ATTACHMENT FOR ADDRESSING MACHINES.

Application filed June 20, 1921. Serial No. 479,063.

To all whom it may concern:

Be it known that I, MILTON F. CHESHIRE, a citizen of the United States, and a resident of the city of Chicago, county of Cook, and 5 State of Illinois, have invented certain new and useful Improvements in Attachments for Addressing Machines, of which the following is a specification.

My invention relates to improvements in 10 Attachments for Addressing Machines especially adapted and arranged for use in perforating such address strips as are used in conjunction with the addressing machine disclosed in my prior application for patent, 15 filed November 29, 1920, Serial No. 427,039. The primary object of the present invention is to provide a simple and efficient attachment for machines printing such strips or lists which is of simple construction, efficient 20 in operation and capable of perforating such strips as a continuation of the process of printing the same.

Other objects will appear hereinafter.

The invention consists in the combinations 25 and arrangements of parts hereinafter described and claimed.

The invention will be best understood by reference to the accompanying drawings forming a part of this specification, and in 30 which,

Fig. 1 is a view of one side of an attachment embodying the invention.

Fig. 2 is a view of the other side thereof.

Fig. 3 is a top plan view of the same.

35 Fig. 4 is a longitudinal section taken on line 4—4 of Fig. 3.

Fig. 5 is a plan view of a form of stencil employed in the attachment.

Fig. 6 is an end view of the attachment.

40 Fig. 7 is a section through one of two punch members employed in the attachment, and

Fig. 8 is a detail view of a portion of an addressing strip produced by the attachment.

45 The preferred form of construction as illustrated in the drawings comprises a suitable frame 10 adapted and arranged to be secured to the rear or delivery end of an ordinary strip printing machine. The form of attachment illustrated is one operating in conjunction with a well known machine now upon the market and known as the Belknap

duplex listing machine. The attachment is adapted and arranged to be secured immediately to the rear of the usual stencil guides 11 and 12 of such a machine adapted and arranged to guide the stencils 13 and 14 in the usual manner. The stencils 13 and 14 are the usual and ordinary stencils employed in said Belknap machine except that some of the stencils 13 are provided with notches 15 in their edges. The stencils 13, it will be noted, do not contain a complete address, including the name of a subscriber to a paper or the like, but merely the name of a city, town or mailing route as shown, said stencils 13 being inserted in the body or run of stencils at the end of the sets of stencils therein constituting addresses in a certain city, town or mailing route and being marked with the name of said route. The Belknap machine, to which reference has been made, is arranged and adapted to apply the address and route names on the stencils 13 to the under side of a strip 17 of paper which is fed through the machine in the usual way and delivered from the rear end thereof, said machine being an old and well known machine for the purpose and requiring no further illustration or description here, it being sufficient to state that said machine is such that by the use of stencils 13 and 14 a complete mailing or route list is applied to the under side of strip 17.

85 My attachment is attached to the rear of such a machine adjacent the rear guide 12 thereof and stencils 13 provided with notches 15 in their edges, said stencils 13 indicating the ends of the various sets of addresses as above explained. A notch 16 is also provided in the rear stencil guide 12 adapted and arranged to register with the notches 15 as the stencils 13 pass across the strip 17 in said guide. As illustrated in Fig. 8 the strip 17 passing from said Belknap machine contains the addresses on its under side as indicated, said addresses being separated into groups by intermediate marks as indicated, the different addresses being indicated by reference numeral 19.

100 The improved attachment constituting the subject matter of the present invention is adapted and arranged to provide the regular perforations 20 between the various addresses or designations on said strip and also

the irregular perforations 21 corresponding with the route designations between said sets of addresses.

To this end a strip guide 22 is arranged 5 in the frame 10 to receive the strip 17 passing from said Belknap machine. Co-operating with the guide 22 are two vertically reciprocating spring held punch members 23 and 24 operable by oscillatory levers 25 10 and 26 and adapted and arranged to form said perforations, the punch 23 forming the oblong perforations 21 adjacent one side of strip 17 and the punch 24 forming the central circular perforations 20 in said strip. 15 The punch 24 is positioned under the lever 26 to be operated at regular intervals upon each operation of said lever to form the regularly spaced central perforations 20 as will be explained more fully hereinafter. 20 The punch 23, however, is arranged to operate only intermittently, and to be unaffected normally by oscillations of lever 25. This is accomplished by arranging a control finger 27 on a guide 28 on the lever 25 beyond 25 the normal path of the plunger 23 but provided with a lateral projection or lug 29 shiftable into the path of said plunger, the arrangement being such that upon each normal downward stroke of the forward end 30 of the lever 25 the upper end of the plunger 23 passes into the angle between the finger 27 and the lateral projection 29, so that said plunger will not be operated under normal circumstances. However the finger 27 is 35 pivotally connected with the upper end of a rocker arm 30 rigidly secured to a rocker shaft 31 mounted on frame 10 and carrying a trigger arm 32 projecting through the notch 16 to ride upon the edges of the stencils and to drop into one of the notches 15 when such occur. The arm 30 is normally drawn outwardly by means of a tension spring 33 which thus yieldingly holds the trigger 32 in contact with the tops of the 40 stencils. The arrangement is such that when the notch 15 in one of the stencils 13 passes into registration with notch 16 and thus with trigger arm 32, said trigger arm drops into said notch 15 and the projection 29 is 45 drawn laterally by the spring 33 into registration with the top of plunger 23, so that the next succeeding movement of lever 25 will cause a corresponding operation of the punch 23 thus forming one of the perforations 21 in the side of the strip 17. It will be observed that the notch 16 and the trigger arm 32 are arranged just beyond the path of the strip 17 so that immediately after each stencil 13 is applied to said strip, 50 a corresponding perforation 21 will be formed therein.

The oscillations of levers 25 and 26 are caused by a master shaft 34 carrying cam members 35 contacting with the under sides 65 of said levers, a spring lever 36 being ar-

ranged across the tops of the said levers as shown to induce simultaneous operation thereof. The master shaft 34 is driven by means of a sprocket 37 arranged to be connected by a suitable sprocket chain with one 70 of the shafts of the said Belknap machine as will be readily understood. Shaft 34 carries a driving disc or plate 38 having a notch 39 in its periphery and carrying a driving pin 40 adapted and arranged to engage the notches 41 in a rose gear 42 fixed to a countershaft 43 of the attachment. A pivoted dog 44 is provided with a nose 45 adapted to enter the notches 41, said nose being provided with bevelled ends 46 co-operating with correspondingly bevelled corners 47 of said notches. A spring 48 rests upon the dog 44 and normally presses the nose 45 into engagement with the notches 41. At its other end the dog 44 is 80 provided with a lug 49 riding upon the periphery of the disc 38 and adapted and arranged to drop into the notch 39 when nose 45 is forced from one of the notches 41. The arrangement is such that upon each 85 revolution of the shaft 34 the pin 40 engages one of the notches 41 and causes a partial revolution of shaft 43, the bevelled edges 47 of notches 41 forcing the pawl nose 45 out of engagement therewith to permit of 90 such partial revolution. At the termination of such partial revolution the nose 45 registers with one of the notches 41 and is forced into engagement therewith by spring 48, being positively held in such engagement 100 by the cam action of the periphery of disc 38 and whereby shaft 43 will be firmly locked against rotation during the intervals between its partial operations as above indicated.

A feed roller 50 is provided with a hub 51 attached to the shaft 43. The periphery of the feed roller 50 is provided with central radiating projecting feed pins 52 adapted and arranged to engage the central perforations 20 in the strip 17 to cause accurate and positive feeding of said strip. A grooved guide roller 53 co-operates with the under side of the roller 50 to hold said strip in engagement with said pins. Another feed roller 54 is arranged above the roller 50 and is secured to a countershaft 55 as shown. The roller 54 is provided with flanges 56 and 57 holding the strip 17 in contact with the roller 50 without blurring of the printing 110 thereon and providing a groove 58 for the accommodation of the pins 52 as shown. A rubber covered tension roller 59 is mounted on a shaft 60 in brackets 61 pivoted at 62 to the top of the frame 10, said roller 59 115 being drawn into yielding contact with the peripheries of flanges 56 and 57 by means of a tension spring 63 and whereby the strip 17 will be held in nice contact with said flanges. A guide roller 64 is provided in 120

brackets 61 to facilitate discharge of the strip 17. Inter-meshing gears 65, 66 and 67 are provided on shafts 43, 55 and 60 respectively and whereby the rollers 54 and 59 5 will be positively operated at each operation of the roller 50 on shaft 43.

The arrangement is such that as each stencil 13 or 14 is fed across and below the path of the strip 17 it pauses momentarily under 10 said strip, said strip also pausing, and during this pause each stencil is applied to the under side of the strip by the normal operation of said Belknap machine. Thereupon the strip 17 is drawn onto the roller 15 50 the exact length between two of the perforations 20 and a new stencil is applied thereto as before, the punch 24 operating constantly and regularly to provide the regularly spaced perforations 20 between the 20 imprints from the different stencils. Upon the next operation after the application of one of the notched stencils 13 to the strip 17 the punch 23 is automatically operated to provide a side perforation 21 to correspond 25 with the imprint of said notched stencil. In this manner the strip 17 normally produced by said Belknap machine without perforation will be automatically provided with the perforations 20 and 21 so that said 30 strip may be employed in the machine or attachment illustrated and described in my said co-pending application mentioned above.

While I have illustrated and described the 35 preferred form of construction for carrying my invention into effect, this is capable of variation and modification without departing from the spirit of the invention. I, therefore, do not wish to be limited to the 40 precise details of the construction set forth, but desire to avail myself of such variations and modifications as come within the scope of the appended claims.

Having described my invention, what I 45 claim as new and desire to secure by Letters Patent, is:—

1. In a machine of the class described comprising strip perforating mechanism; a stencil guide arranged to guide stencils into 50 operative relation with said strip for printing thereon; and means operable by said stencils for actuating said perforating mechanism to perforate said strip in operative relation with the printing applied by 55 the actuating stencil, substantially as described.

2. A machine of the class described comprising strip perforating mechanism; a stencil guide in operative relation with said 60 strip, said stencils being provided with notches in their edges; and means operable by said notches controlling said perforating mechanism, substantially as described.

3. A machine of the class described comprising strip feeding and perforating mech-

anism; a strip guide leading to said mechanism; a stencil guide crossing said strip guide; stencils fitting said stencil guide; and means operable by stencils in said stencil guide controlling said perforating mech- 70

anism, substantially as described. 4. A machine of the class described comprising strip feeding and perforating mechanism; a strip guide leading to said mechanism; a stencil guide crossing said strip 75 guide; stencils fitting said stencil guide and provided with notches in their edges; and means operable by notches in stencils in said stencil guide controlling said perforating mechanism, substantially as described. 80

5. A machine of the class described comprising strip feeding and perforating mechanism; a strip guide leading to said mechanism; a stencil guide crossing said strip guide, said stencil guide being provided with 85 a notch giving access to the edges of the stencils therein; stencils fitting said stencil guide and provided with notches in their edges registering with the notch in said guide; and means operating through the 90 notch in the stencil guide and operable by notches in said stencils controlling said perforating mechanism, substantially as described.

6. A machine of the class described comprising strip feeding and perforating mechanism; a strip guide leading to said mechanism; a stencil guide crossing said strip guide, said stencil guide being provided with a notch giving access to the edges of 95 the stencils therein; stencils fitting said stencil guide and provided with notches in their edges registering with the notch in said guide; a trigger operating in the notch in the stencil guide and arranged to enter the 100 notches in the stencils; and means operable by entry of said trigger into said stencil notches controlling said perforating mechanism, substantially as described.

7. A machine of the class described comprising strip feeding mechanism; a constantly operating punch arranged to perforate said strip at regular intervals; an intermittently operating punch arranged to perforate said strip when operated; and means 115 for operating said intermittent punch at irregular intervals, substantially as described.

8. A machine of the class described comprising strip feeding mechanism; a constantly operating punch arranged to perforate said strip centrally at regular intervals; an intermittently operating punch arranged to perforate said strip at one side when operated; and means for operating said intermittent punch at irregular intervals, sub- 120 stantially as described.

9. A machine of the class described comprising strip feeding mechanism; a constantly operating punch arranged to perforate said strip at regular intervals; an inter- 130

mittently operating punch arranged to perforate said strip when operated; a stencil holder in operative relation with said strip; and means operable by said stencils controlling said intermittent punch, substantially as described.

10. A machine of the class described comprising strip feeding mechanism; a constantly operating punch arranged to perforate said strip centrally at regular intervals; an intermittently operating punch arranged to perforate said strip at one side when operated; a stencil holder in operative relation with said strip; and means operable by said stencils controlling said intermittent punch, substantially as described.

11. A machine of the class described comprising strip feeding mechanism; a constantly operating punch arranged to perforate said strip at regular intervals; an intermittently operating punch arranged to perforate said strip when operated; a stencil holder in operative relation with said strip, some of said stencils being provided with notches in their edges; and means operable by said notches controlling said intermittent punch, substantially as described.

12. A machine of the class described comprising strip feeding mechanism; a constantly operating punch arranged to perforate said strip centrally at regular intervals; an intermittently operating punch arranged to perforate said strip at one side when operated; a stencil holder in operative relation with said strip, some of said stencils being provided with notches in their edges; and means operable by said notches controlling said intermittent punch, substantially as described.

13. A machine of the class described comprising strip feeding mechanism; a constantly operating punch arranged to perforate said strip at regular intervals; an intermittently operating punch arranged to perforate said strip when operated; a stencil holder in operative relation with said strip, some of said stencils being provided with notches in their edges; and means operable by said notches controlling the operation of said intermittent punch mechanism, substantially as described.

arranged to rest upon the edges of said stencils and enter the notches therein; and means operable by entry of said trigger to said notches controlling said intermittent punch, substantially as described.

14. A machine of the class described comprising strip feeding mechanism; a constantly operating punch arranged to perforate said strip centrally at regular intervals; an intermittently operating punch arranged to perforate said strip at one side when operated; a stencil holder in operative relation with said strip, some of said stencils being provided with notches in their edges; a spring held trigger arranged to rest upon the edges of said stencils and enter the notches therein; and means operable by entry of said trigger to said notches controlling said intermittent punch, substantially as described.

15. A machine of the class described comprising strip feeding rollers, one of said rollers being provided centrally with projections adapted and arranged to enter and engage central perforations in said strip; constantly operating punch mechanism adapted and arranged to form said central perforations in said strip as it passes to said feed rollers; intermittently operating punch mechanism arranged to provide perforations in said strip when operated; a stencil guide crossing the path of said strip; stencils in said guide, some of said stencils having notches in their edges; a spring held trigger normally riding upon the edges of said stencils and adapted and arranged to enter said notches; and means operable by entry of said trigger in said notches controlling the operation of said intermittent punch mechanism, substantially as described.

In testimony whereof I have signed my name to this specification in the presence of two subscribing witnesses.

MILTON F. CHESHIRE.
